UNITED STATES PATENT OFFICE.

RALPH S. BENNETT, OF PITTSFIELD, MASSACHUSETTS. ASSIGNOR TO GENERAL ELECTRIC COMPANY, A CORPORATION OF NEW YORK.

DESIGN FOR A FUSE CONTAINER.

Application filed January 27, 1928. Serial No. 25,052. Term of patent 14 years.

To all whom it may concern:

Be it known that I, RALPH S. BENNETT, a citizen of the United States, residing at Pittsfield, in the county of Berkshire, State of Massachusetts, have invented a new, original, and ornamental Design for Fuse Containers, of which the following is a specification, reference being had to the accompanying drawing, forming a part thereof.

The drawing is a perspective view of a container showing my new design.

I claim:

The ornamental design for a fuse container as shown.

In witness whereof, I have hereunto set my hand this twenty-third day of January, 1928.

RALPH S. BENNETT.
